(57) **CLAIM**

The ornamental design for a laboratory pipette stand, as shown and described.

DESCRIPTION

FIG. 1 is a left, front, top perspective view of the first embodiment of a laboratory pipette stand showing my new design;

FIG. 2 is a right, front, top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a left, front, top perspective view of the second embodiment of a laboratory pipette stand;

FIG. 10 is a right, front, top perspective view thereof;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top plan view thereof; and,

FIG. 16 is a bottom plan view thereof.

The broken lines in the drawings depict portions of the laboratory pipette stand that form no part of the claimed design.
